(57) **CLAIM**

The ornamental design for a myofascial release device, as shown and described.

DESCRIPTION

FIG. 1 is a front top right side perspective view of a myofascial release device showing our new design; FIG. 2 is a front elevation view thereof;

FIG. 3 is a rear elevation view thereof;

FIG. 4 is a right-side elevation view thereof;

FIG. 5 is a left side elevation view thereof;

FIG. 6 is a top plan view shown at an enlarged scale thereof; and,

FIG. 7 is a bottom plan view shown at an enlarged scale thereof.

The broken lines illustrate portions of the myofascial release device which form no part of the claimed design.

1 Claim, 7 Drawing Sheets
